UNITED STATES PATENT OFFICE.

GEORGE ALBERT ANSELL, OF TORONTO, ONTARIO, CANADA, ASSIGNOR TO DUNLOP
TIRE & RUBBER GOODS COMPANY, LIMITED, OF TORONTO, CANADA.

HOSE.

1,178,484.

Specification of Letters Patent.

Patented Apr. 11, 1916.

Application filed June 15, 1914. Serial No. 845,156.

To all whom it may concern:

Be it known that I, GEORGE ALBERT ANSELL, of the city of Toronto, in the county of York and Province of Ontario, Canada, 5 a subject of the King of Great Britain, have invented certain new and useful Improvements in Hose, of which the following is a specification.

This invention relates to flexible hose such 10 as employed for the transmission of fluids, and my object is to provide such hose with a protective jacket or coating which will adapt the hose particularly for the rough use to which hose is frequently subjected in 15 mining operations or other hard service.

I attain my object by forming and applying to the hose a jacket of rubberized fabric in which the threads of the fabric exposed at 20 the surface are mainly normal to the surface 20 of the jacket thus presenting their ends instead of their lengths at the said surface.

This jacket is formed and applied in the manner hereinafter described and illustrated in the accompanying drawings in 25 which—

Figure 1 is a perspective view illustrating the method of forming the protective jacket; Fig. 2 a development of the cylindrical surface of Fig. 1; Fig. 3 a perspective view 30 of a portion of the strip of which the jacket is formed; and Fig. 4 a perspective view of a portion of the finished hose.

In the drawings like letters of reference indicate corresponding parts in the different figures.

In constructing the protective jacket I first build up on a cylindrical mandrel a plurality of plies 1 of ordinary rubber impregnated fabric preferably the duck commonly employed in hose and rubber tire construction.

The fabric may be applied in successive layers or by the simple process of wrapping it on the mandrel until a sufficient thickness 45 has been built up. A sufficient number of layers or plies are so built up on the mandrel as to form a thickness of preferably about one half inch. The roll of fabric is then spirally cut to form a strip 2 preferably about one eighth of an inch thick, and of a width equal to the thickness of the fabric as built up on the mandrel. This

strip 2 when straightened out appears as shown in Fig. 3.

Owing to the method of cutting, only the 55 ends of the threads of the fabric appear at the surfaces of this strip as will appear on reference to Fig. 2 which is a development of the surface of the roll of fabric built up on the mandrel as illustrated in Fig. 1. 60

In Fig. 2 the lines *a* represent the lines of the spiral cutting, and the lines *b* and *c* threads of the fabric.

If the fabric be applied as shown with one set of threads running lengthwise of the 65 mandrel and the other set of threads running circumferentially round the mandrel one half of the threads of the fabric will lie normal to the surfaces of the strip shown in Fig. 3, the other threads though showing 70 only their ends at the surfaces of the strip extend diagonally through the same. If the fabric were applied on the bias to the mandrel shown in Fig. 1, all the threads would extend diagonally through the strip, their 75 ends only showing at the surfaces. After the carcass of the hose has been built up a strip formed as directed is wound spirally about it, the edges of the strips butting as shown, with one of the cut surfaces of the 80 strip forming the exterior surface of the hose. When the completed hose has thus been built up it is subjected to vulcanization in the usual way. The jacket thus in effect becomes an integral part of the hose, and the 85 edges of the strip forming the jacket becomes also in effect integrally united.

From the construction described it will be evident that no fabric is exposed at the external surfaces of the jacket in such a 90 manner that the threads may be caught and torn by rough surfaces with which the hose may contact. This makes the hose exceedingly valuable for use in mining operations where the hose necessarily has to be dragged 95 over rough rocky surfaces which are liable to cut and tear the surface of the hose.

I have demonstrated by careful experiment that a protective jacket, such as described, adds very materially to the life of 100 the hose, owing to the resistance to wear of the "endgrain" fiber.

While I find it preferable to form the jacket on a mandrel it will be evident that

it may also be formed on the flat and cut into straight strips, which could then be spirally wound on the hose in the same manner as the spirally cut strips formed on the 5 mandrel.

What I claim as my invention is:

Hose provided with a jacket comprising a strip spirally wound on the hose with its edges butting, said strip comprising rubber.

impregnated textile fabric displaying the ends of threads at the exterior surface of the jacket.

Toronto, this 1st day of June, A. D. 1914.

GEORGE ALBERT ANSELL.

In the presence of—

J. EDW. MAYBEE,

E. P. HALL.
